UNITED STATES PATENT OFFICE

FRED P. REINLE, OF OAKLAND, CALIFORNIA, ASSIGNOR TO WEST COAST SOAP COMPANY, OF OAKLAND, CALIFORNIA, A CORPORATION

SCOURING SOAP POWDER

No Drawing.

Application filed September 19, 1927. Serial No. 220,634.

The invention forming the subject matter of this application relates to scouring soap powder, and particularly to soap powders which may be used either for the cleaning of metal-ware or for dissolving stains or grime on the human skin.

The principal object of the invention is the production of a scouring soap powder to be applied to the surfaces of metal-ware for cleaning and brightening the same without scratching.

Another object of the invention is to produce a soap powder which can be used also for removing any stains or grime from the human skin, thereby rendering valuable service for persons employed in such work which is liable to produce stains and grime on the hands, or other parts of the body.

My composition consists of a mixture of a vegetable oil, a sodium hydroxide, neutral soda which consists of bicarbonate and carbonate of soda, a liquid alkaline soap solution, and a cementing material such as volcanic ash.

In preparing the composition I prefer to use the ingredients in about the following proportions: viz,

200# cocoanut oil or palm kernel oil,

107# caustic soda,

3c 38° Baumé sodium hydroxide solution of lye,

150# water,

70# neutral soda consisting of bicarbonate and carbonate of soda, and

35 900# volcanic ash.

To obtain good results, mix the cocoanut or palm kernel oil and the caustic soda, lye 38° Baumé which is saponified and formed into a soap. Then take the 150 pounds of water

40 heated to 180° F. and dissolve in it 70 pounds of neutral soda in powdered form which is added to the liquid soap solution. Then the volcanic ash is added which is thoroughly saturated with the soap solution in a mixer.

45 From there the mixture is either run through

a continuous dryer or into frames and dried. Then it is cut into bars and ground.

For polishing metal ware the scouring powder is applied to the surface thereof with a damp cloth, then rinsed off with clean water and dried.

For cleaning the hands of a person, first the hands are wet, then a small amount of the powder is sprinkled thereon. A lather is formed by washing the hands, the lather is rubbed well into any stains or grime, and dissolves the same. The aforescribed scouring soap powder is not only harmless to the human skin, but the daily use thereof aids in keeping it in smooth and clean condition.

My composition is light, very efficient and it possesses in a high degree all the desired properties of a scouring powder used for cleaning and polishing metal-ware or for keeping the hands of a person in perfect condition.

I claim:

1. A cleaning composition in a powdered condition, formed by mixing the following ingredients: vegetable oil and caustic soda 70 lye 38° Baumé in equivalent amounts; neutral soda, consisting of bicarbonate and carbonate of soda; and volcanic ash.

2. A cleaning composition in a powdered condition, formed by mixing the following ingredients: cocoanut oil and caustic soda 75 lye 38° Baumé in equivalent amounts; neutral soda, consisting of bicarbonate and carbonate of soda; and volcanic ash.

3. A cleaning composition in a powdered 80 condition, formed by mixing the following ingredients in the following proportions: 200 lbs. vegetable oil; 107 lbs. caustic soda lye 38° Baumé; 70 lbs. neutral soda, consisting of bicarbonate and carbonate of soda; and 900 lbs. 85 volcanic ash.

4. A cleaning composition in a powdered condition, formed by mixing the following ingredients in the following proportions: 200 lbs. cocoanut oil; 107 lbs. caustic soda lye 90

38° Baumé; 70 lbs. neutral soda, consisting of bicarbonate and carbonate of soda; and 900 lbs. volcanic ash.

5. A cleaning composition in a powdered condition, formed by mixing the following ingredients: caustic soda and vegetable oil in equivalent amounts; neutral soda, consisting of bicarbonate and carbonate of soda; a liquid soap solution; and volcanic ash.

10 In testimony whereof I affix my signature.
FRED P. REINLE.
